CLAIM

The ornamental design for a combined carpet and floor dryer, as shown and described.

DESCRIPTION

FIG. 1 is a perspective view of a combined carpet and floor dryer showing my new design;

FIG. 2 is a front elevational view with the rear elevational view being a mirror image thereof;

FIG. 3 is a right side elevational view with the left side being a mirror image thereof;

FIG. 4 is a top view thereof; and,

FIG. 5 is a bottom view thereof.

The broken line showing of casters in FIGS. 1, 2, and 5 is for illustrative purposes only and forms no part of the claimed design.

FIG. 1

FIG. 2

FIG. 3

FIG. 4

FIG. 5
